by *J. E. Roberts* Att'y.

UNITED STATES PATENT OFFICE.

ALBEN E. LUNDELL, OF NEW YORK, N. Y., ASSIGNOR TO WESTERN ELECTRIC COMPANY,
INCORPORATED, OF NEW YORK, N. Y., A CORPORATION OF NEW YORK.

TELEPHONE SYSTEM.

1,272,280.

Specification of Letters Patent.

Patented July 9, 1918.

Application filed October 6, 1916. Serial No. 124,066.

To all whom it may concern:

Be it known that I, ALBEN E. LUNDELL, a citizen of the United States, residing at New York, in the county of Bronx and State of New York, have invented certain new and useful Improvements in Telephone Systems, of which the following is a full, clear, concise, and exact description.

This invention relates to indicating systems, and more particularly to telephone exchange systems in which means are provided for conveying a signal to an operator for indicating the designation of a calling subscriber's line.

For this purpose it has been proposed to provide a normally idle controlling apparatus individual to an operator's position, or a constantly moving apparatus common to a plurality of operators' positions for controlling at the operator's position signals designating calling lines.

The drawback of such arrangements is that if one controlling apparatus is provided for each position, a large number of such apparatuses have to be provided for a telephone exchange system, and if a constantly operating common apparatus is provided, such apparatus will be subject to severe, and to a certain extent unnecessary use, and furthermore, requires the consumption of much current.

According to one feature of the present invention, means, such as a controlling apparatus of the sequence switch type, is provided in common to a plurality of operators' positions for controlling the actuation of any one of a plurality of line indicating signals, said controlling apparatus having a normal position in which it rests when not in use.

According to another feature of the present invention, a controlling apparatus such as a sequence switch producing a definite number of operations, such as the opening or closure of an electrical circuit, during one complete movement, is provided with means for causing the production of a definite number of operations, no matter in what position said sequence switch is required to produce said definite number of operations.

In other words, a sequence switch adapted to open twice an electrical circuit while moving from its normal position into its last position, said circuit changes being produced, for instance, in positions $4\frac{1}{2}$ and $12\frac{1}{2}$

of said sequence switch, will cause two electrical changes in the circuit even if it is operated to produce the first change when moving through position 12. This is attained by causing said sequence switch to perform always two rotations when called into service, thus making sure that one rotation will be complete. If the sequence switch is taken into use when standing in its normal position, the circuit interruptions produced during its second rotation will be of no effect.

In another aspect, this invention may be defined as providing a controlling apparatus having a definite normal position and adapted to produce a definite number of operations, such as circuit interruptions or closures, and may be used for producing these operations even if it does not stop in its normal or resting position.

The drawing shows a telephone station and an operator's position to which such subscriber's station may be connected, and an indicating arrangement devised in accordance with the present invention.

A sequence switch 17 may be of the structure described in Patent No. 1,127,808. This sequence switch has eighteen positions and controls in its various positions the closing and opening of the sequence switch contacts diagrammatically shown in the drawings. A master contact 18, which is closed in all positions except 1, controls the movement of the sequence switch toward position 1 after the switch has been moved out of this position.

Sequence switch 17 is common to a plurality of operators' positions (only two operators' telephone sets, 2 and 2', are shown) and controls the actuation of lamps 41, 26 or 47, provided at each operator's position, and designating the number or class of the calling subscriber's line.

A conductor 16' is connected in multiple to the left-hand back contact of a relay 15 and to the contacts of similar relays (not shown), one provided at each operator's position.

No means are disclosed for extending a calling line to an operator's position, as this does not affect the present invention. This means may be either automatic, such as a line finding or trunk finding switch, or manual, such as a plug and jack. All the subscribers' lines belonging to one class or

group are represented by a connection to sequence switch contact 4. Similarly, all the other subscribers' lines belonging to other classes are represented by connections to 5 sequence switch contacts 40 and 45, respectively. Conductor 19, individual to subscriber's line A, may be connected by the above mentioned automatic or manual means to a conductor 6 leading to a contact 10 of a listening key 3 of operator's position No. 2, or to a conductor 6' leading to a contact of the listening key of operator's position No. 2'.

Another subscriber's line B, belonging to 15 a group of lines, other than line A, may also be associated with operators' positions. 2 or 2' and a conductor 19', individual to line B, may be connected to conductors 6 or 6'.

The subscriber at station 1, desiring to obtain 20 a connection with an operator's position No. 2, removes his receiver from the switch-hook and causes, in the well-known manner, the extension of his line A to a trunk or cord circuit C, and the extension of conductor 19 to conductor 6. The operator thereupon depresses her listening key 3, thus connecting her telephone head set to the calling subscriber's line.

Assuming that sequence switch 17 is standing 30 in position 1, upon the actuation of the listening key 3, a circuit is closed from ground through a sequence switch contact 4, a resistance lamp 5, conductor 6, a key contact 7, and the winding of a relay 8, to grounded battery. Relay 8 closes a circuit from ground, through its armature and front contact, the winding of a relay 9, conductors 10 and 11, and a key contact 12, to grounded battery. Relay 9 becomes energized 35 and locks up its winding through its left-hand armature and contact 13. Relay 9 also closes a circuit from ground through its left-hand armature, contact 14, the left-hand armature and back contact of a relay 40 15, a contact 16 and the power magnet of sequence switch 17, to grounded battery. The sequence switch is moved out of position 1, and under the control of its master contact 18 from position to position, until its 45 50 circuit is broken in position 1.

While the sequence switch is moving from position 1 to 4, the above-traced circuit, including lamp 5 and relay 8, is closed at sequence switch 4. As soon, however, as the 55 sequence switch leaves position 4, and until it reaches position 5, sequence switch contact 4 is open, resulting in the deenergization of relay 8. Relay 9 being locked up, a circuit is closed from ground, through the armature 60 and back contact of relay 8, the right-hand front contact and armature of relay 9, the armature and back contact of relay 20, the winding of relay 21, conductors 10 and 11, and key contact 12 to grounded battery. 65 Relay 21 pulls up and closes a locking cir-

cuit for itself through its left-hand front contact and armature.

When the sequence switch reaches position 5, the relay 8 again becomes energized. As soon as the sequence switch reaches position 6 and until it moves out of position 13, a circuit is closed from ground through a sequence switch contact 22, the winding of relay 20, and key contact 23, to grounded battery. Relay 20 becomes energized. As soon as the sequence switch moves out of position 12 and until it reaches position 13, the circuit, including lamp 5 and relay 8, is again opened. Upon the deenergization of relay 8, a circuit is closed from ground through 80 the armature and back contact of relay 8, the right-hand front contact and armature of relay 9, the armature and front contact of relay 20, the winding of a relay 24, conductor 11 and key contact 12, to grounded 85 battery. Relay 24 pulls up and closes a locking circuit for itself at its left-hand front contact and armature. Relays 21 and 24 being energized, a circuit is closed from grounded battery, through the right-hand 90 armature and a contact 25 of relay 21, lamp 26, the right-hand front contact and armature of relay 24, and the high resistance right-hand winding of a relay 27, to ground. Relay 27 becomes energized, but lamp 26, 95 which designates the class of subscriber 1, does not become lighted while in series with the high resistance winding of relay 27.

As soon as sequence switch 17 reaches position 18, a circuit is closed from grounded 100 battery, through a sequence switch contact 28, the armature and front contact of relay 27, and the left-hand winding of a relay 29, to ground. Relay 29 pulls up and closes a locking circuit for itself extending from 105 ground through its right-hand front contact, armature and winding, conductors 10 and 11, and key contact 12, to grounded battery.

Sequence switch 17 then moves into position 1 and due to the fact that the left-hand back contact of relay 15 is still closed, the sequence switch continues its rotation. When it again reaches position 17 a circuit is closed from grounded battery, through 110 sequence switch contact 30, the left-hand armature and front contact of relay 29, and the left-hand winding of relay 15 to ground. Relay 15, by attracting its right-hand armature, closes a locking circuit for itself 115 through conductors 10 and 11, and by attracting its left-hand armature, opens the driving circuit for sequence switch 17, whereby this switch after it has been moved by its master contact 18 into position 1, will 120 be stopped.

Due to the attraction of the left-hand armature of relay 15, a circuit is closed from ground through the left-hand armature and contact 14 of relay 9, the left-hand armature 125

and front contact of relay 15, the low resistance winding of relay 27, the right-hand armature and front contact of relay 24, lamp 26, contact 25, and the right-hand armature 5 of relay 21 to grounded battery. Lamp 26 will now light up and the operator, noticing lamp 26 lighted, will know the class into which subscriber 1 belongs.

Upon the restoration of the listening key, 10 contact 12 is opened, resulting in the unlocking of relays 15, 29, 9, 21 and 24, whereupon lamp 26 is extinguished and the apparatus is ready for use in connection with another call.

15 The purpose of causing the sequence switch 17 to complete two revolutions for controlling the lighting of a class of service indicating lamp, is to insure the proper operation of relays 20, 21 and 24 in whatever 20 position the sequence switch 17 may be when the operator depresses listening key 3.

Assume that sequence switch 17 is moving through position 12 when the operator depresses listening key 3. Relay 8 becomes 25 energized and causes the energization and locking up of relay 9 in the manner above described. When sequence switch 17 moves from position 12 to position 13, *i. e.*, in position 12½, the sequence switch opens the circuit of relay 8, and this relay in turn causes the energization of relay 24, relay 20 being energized at this time. In position 13 of the sequence switch, relay 8 again becomes energized over its original energizing circuit, and if the sequence switch would not be caused to complete a second revolution, relay 21 would not become energized in response to the initiation of this call, because, as above described, this relay operates in position 4½ 30 of the sequence switch. For this reason, instead of lamp 26, lamp 41 would be connected in circuit and thus a wrong class of service indication would be given to the operator. However, as described in connection

45 with the above assumed case, due to the provision of sequence switch contacts 28 and 30 and relay 29, the sequence switch is caused to complete another revolution. When, during this second rotation, the sequence switch 50 leaves position 4, relay 8 would again become deenergized, and would cause the operation of relay 21. In position 12½ of the sequence switch, relay 24 will not be affected, due to the fact that it has already been locked up.

55 Relay 15 cannot become energized in position 17 of the sequence switch when this sequence switch performs its first rotation, because relay 29 is not energized at that time. During the second revolution of the 60 sequence switch, relay 15 will be energized in the above described manner and will cause the stopping of the sequence switch in position 1. Relays 21 and 24 being energized, lamp 26 will be lighted.

65 If a call is initiated on line B, then also

upon the actuation of the listening key 3, relay 8 becomes energized. This relay stays energized until the sequence switch leaves position 12. Relays 9 and 20, having been energized and locked up in the meantime, 70 while sequence switch 17 is moving from position 12 to position 13, relay 8 becomes deenergized and a circuit is established from ground, through the armature and back contact of relay 8, the right-hand armature and front contact of relay 9, the armature and front contact of relay 20, the winding of relay 24, conductor 11, and key contact 12 to grounded battery.

In position 13 of the sequence switch relay 8 again becomes energized. At this time a circuit is closed from grounded battery, through the right-hand armature and back contact of relay 21, a lamp 41 indicating the class of line B, the right-hand armature and front contact of relay 24, and the high resistance right-hand winding of relay 27 to ground. Relay 27 becomes energized, but lamp 41 will not light up in series with this high resistance winding. Relay 8 will be 90 maintained energized while the sequence switch is moving from position 13 to position 1. When the sequence switch reaches position 18, the circuit of relay 29 is completed and this relay locks up, and when 95 during its second revolution the sequence switch reaches position 17, the circuit of relay 15 is completed and this relay also locks up. Upon the opening of the left-hand front contact of relay 15, the driving 100 circuit of the sequence switch is opened and this switch is stopped in position 1.

Due to the closure of the left-hand front contact of relay 15, the circuit for lighting lamp 41 is completed through the low resistance winding of relay 27. The operator, noticing lamp 41 lighted, will know the class of the subscriber calling.

Supposing that a subscriber of a class to which sequence switch contact 45 is individual is calling, relay 8 will become energized upon the depression of the listening key, and causes in turn the energization of relay 9. The driving circuit of the sequence switch 17 is then closed. While the sequence switch is moving from position 1 to position 4, relay 8 is maintained energized. As soon as the sequence switch leaves position 4, relay 8 becomes deenergized and closes a circuit for relay 21, relay 20 being deenergized at this time. Relay 21 locks up its winding and closes a circuit from grounded battery, through its contact 46, a lamp 47, characteristic of this class of subscribers, the right-hand back contact and armature of relay 24, and right-hand high resistance winding of relay 27, to ground. Relay 27 becomes energized but lamp 47 does not light up while in series with the high resistance winding of this relay. Relay 8, being main- 125

130

tained energized while sequence switch 17 is moving from position 5 to position 1, the energization of relay 20 in positions 6 to 13 of the sequence switch will have no effect on relay 24. Relay 27 causes the energization of relay 29 and this in turn the energization of relay 15. The sequence switch 17 is then stopped in position 1 and lamp 47 allowed to light up, indicating the class of the subscriber calling.

What is claimed is:

1. In a telephone exchange system, a plurality of lines, characteristic signaling means for each line, a normally resting switching device common to the signaling means of said lines, and means controlled by said switching device for simultaneously controlling the actuation of a plurality of said signaling means in a manner characteristic for a plurality of calling lines.
2. In a telephone exchange system, a plurality of lines, a plurality of trunks, characteristic signaling means for each line at each trunk, a normally resting switching device common to said trunks, means for extending any one of said lines when calling to any one of said trunks, and means operative thereupon and controlled by said switching device for simultaneously actuating at each trunk to which a calling line has been extended the signaling means characteristic for the extended calling lines.
3. In a telephone exchange system, a plurality of lines of different classes, a plurality of trunks, a plurality of operators' telephone sets, means operative upon the initiation of a call on any one of said lines for extending it to any one of said trunks, a listening key for each operator's telephone set, an electrical circuit closed upon the actuation of any one of said listening keys, a switch normally at rest for controlling said circuit, means responsive to the actuation of any one of said listening keys for starting the operation of said switch, and means depending on the class of the line calling for causing said switch to change the electrical condition of said circuit in a predetermined manner.
4. In a telephone exchange system, a plurality of lines, a plurality of operators' positions, means for extending any one of said lines to any one of said positions, a plurality of signals one for each of said lines at each of said operators' positions, and means normally at rest and common to said operators' positions for simultaneously controlling the actuation of said signals.
5. In a telephone exchange system, a plurality of lines, a plurality of operators' positions, means for extending any one of said lines to any one of said operators' positions, a plurality of signals one for each line at said operators' positions, means normally at rest and common to said operators' positions,

and means responsive to the extension of calling lines to operators' positions to operate said second mentioned means to simultaneously control the actuation of the signals individual to the calling lines.

70

6. In a telephone exchange system, a plurality of lines, a plurality of operators' telephone sets, a listening key for each of said sets for connecting it into telephonic association with a calling line, a plurality of signals at each of said operators' positions, one signal being individual to each line, a switch common to said operators' positions and normally at rest, and means responsive to the actuation of the listening keys at all of said operators' positions for causing said switch to actuate at each position the signal individual to the calling line extended to the position.

75

7. In combination, an electrical circuit, a switch having a normal and a plurality of operating positions, means actuated in certain operating positions of said switch for changing the electrical condition of said circuit, and means operable in any position of said switch for causing it to produce said circuit changes.

85

8. In combination, an electrical circuit, a switch having a normal and a plurality of operating positions, means for causing said switch to change the electrical condition of said circuit a predetermined number of times while moving from its normal position through all its operating positions into its normal position, and means for causing said switch to produce said predetermined number of circuit changes in whatever position it is caused to produce the first circuit change.

95

9. In combination, an electrical circuit, a switch having a normal and a plurality of operating positions, an actuating magnet for said switch, an energizing circuit for said magnet, means effective only when said switch is in its normal position for closing said energizing circuit, means operated in certain operating positions of said switch for producing a change in said electrical circuit, said changes being of a predetermined number, and means for causing said switch to produce said predetermined number of changes in the circuit if the energizing circuit is closed while the switch is traveling through any of its operating positions.

105

10. In combination, a plurality of electrical circuits, a switch having a normal and a plurality of operating positions, an actuating magnet for said switch, an energizing circuit for said magnet having a plurality of branches one branch being provided for each electrical circuit, a circuit closing device in each of said branches, a contact in a common portion of said energizing circuit closed only in the normal position of said switch, means operative upon the ac-

115

120

125

130

- tuation of any one of said circuit closing devices and said contact for maintaining said magnet energized until the switch has moved through its operating positions into 5 its normal position, means actuated in certain positions of said switch for producing changes in one of said electrical circuits, means operative in certain other positions of said switch for producing changes in another one of said electrical circuits, and 10 means for making said last two mentioned means effective during one complete movement of said switch.
11. In combination, a plurality of electrical circuits, a switching device normally at rest, means for operating said switching device to simultaneously produce changes in said circuits at varying intervals, a signaling device responsive to said circuit changes 15 associated with each of said circuits, and means associated with each of said circuits for determining the number of the effective changes to be produced in the circuit.
12. In combination, an electrical circuit, 20 a rotatable switching device normally at rest, means operable during each complete rotation of said switching device for producing a certain number of changes in said electrical circuit, a responsive device controlled in accordance with the changes produced in said circuit, automatic means for 25 causing a started switching device to complete two revolutions, and means for making the circuit changes produced during the second revolution of said device ineffective.
13. In combination, an electrical circuit, 30 a rotatable switching device normally at rest, means operable during each complete rotation of said switching device for producing changes of a certain character in said electrical circuit, a responsive device controlled in accordance with the changes produced in said circuit, automatic means for 35 causing a started switching device to complete two revolutions, and means for making the circuit changes produced during the second revolution of said device ineffective.
14. In combination, an electrical circuit, 40 a rotatable switching device normally at rest, means operable in any position of said switching device for associating it with said circuit, means operable during each complete 45 rotation of said switching device for producing a certain number of changes in 50 the associated electrical circuit, a responsive device controlled in accordance with the changes produced in said circuit, automatic means for causing a started switching device to complete two revolutions, and means for rendering effective only circuit changes equal in number to the changes produced during one revolution of said switching device.
15. In combination, an electrical circuit, 55 a rotatable switching device normally at rest, means operable in any position of said device for associating it with said circuit, means operable during each complete rotation of said switching device for producing 60 changes of a certain character in said electrical circuit, a responsive device controlled in accordance with the changes produced in said circuit, automatic means for causing a started switching device to complete a 65 plurality of revolutions, means for disconnecting said device from said circuit only after the completion of said plurality of revolutions, and means for making effective only circuit changes equivalent in character 70 to the changes produced during one complete rotation of said device.
16. In combination, an electrical circuit, 75 three signals individual thereto, a relay controlling at its front contacts the circuits 80 of the first and second of said signals, and at its back contact the circuit of the third signal, another relay controlling at its front contact the circuit of said third signal and the circuit of the second signal, and at its 85 back contact the circuit of the first signal, a third relay controlling at its back contact the circuit of said first mentioned relay, and at its front contact the circuit of said second mentioned relay, a switching device for controlling 90 said electrical circuit, means controlled by said switching device for producing at varying intervals changes in said circuit, means responsive to said changes in said circuit for operating said first and second mentioned relays, and means depending 95 on the time interval elapsing between two changes for controlling the operation of said third mentioned relay.
- In witness whereof, I hereunto subscribe 100 my name this 4th day of October, A. D. 1916.

ALBEN E. LUNDELL.
